FLUXING DEVICES

Arthur P. Meier, Bloomfield, and Sylvester P. Denison, Belleville, N. J., assignors to Westinghouse Electric Corporation, East Pittsburgh, Pa., a corporation of Pennsylvania

Application December 3, 1953, Serial No. 395,996

4 Claims. (Cl. 113—95)

This invention relates to fluxing devices for lamp base outlets, and more particularly to a fountain type of device for that purpose.

Efforts have been made in the past to apply flux to terminal pins by dipping the pins into a pool of flux or by depressing the pins into a sponge material at the top of a pool of flux. Such methods are not applicable practically for applying flux to a lamp base terminal in view of the short length of projecting wire and need to confine the flux in close vicinity thereto.

An object of the present invention is to provide an improved fluxing device wherein the area upon which the flux is applied is limited to the immediate area to be soldered.

Another object of the invention is to repetitiously apply the same amount of flux to successively presented lamp base terminals.

Another object of the invention is to provide a repetitiously equal amount of flux to the successively presented lamp base terminals irrespective of the quantity of flux still available in the reservoir.

Another object of the invention is to provide a device of the character indicated which will function properly and effectively at high speed for meeting needs of present-day automatic lamp machines which fabricate lamps at the rate of 1500 or more per hour.

Other objects of the invention will be apparent to persons skilled in the art to which it appertains as the description proceeds, both by direct recitation thereof and by implication from the context.

Referring to the accompanying drawings in which like numerals of reference indicate similar parts throughout the several views:

Figure 1 is a sectional elevation of a portion of a lamp-fabricating machine showing a lamp in a holder at an indexed position at which the fluxing device of the present invention is located;

Figures 2 and 3 are vertical sectional views of the device respectively in positions disengaged from the lamp and engaged therewith; and

Figures 4, 5 and 6 are cross sections of Fig. 2 taken respectively on lines IV—IV, V—V and VI—VI thereof.

In the specific embodiment of the invention illustrated in said drawings, the machine provides a spider or other conveyor 10 (Fig. 1) having a plurality of holders 11 of which one is shown for a lamp 12 which successively indexes from station to station as well understood in this art. Fixed, as by a bracket 13, at one of the stations is the device of the present invention in such relation to the indexing holder that it will be directly above the lamp carried by a holder when indexed to that station.

The device provides an upright cylindrical reservoir 14 (Figs. 1-3) with an external bearing sleeve 15 thereon for mounting the reservoir to reciprocate vertically in the bracket 13. As best shown in Figures 1 and 4, studs 16 on a common diameter of the sleeve 15 project outwardly through vertical slots 17 in the bracket and

are trunnioned in links 18 at opposite sides of said bracket. The upper ends of the links are pivotally hung from the forked ends of a rocker arm 19 which spans the bracket and which is operated in timed relation to the indexing mechanism so that the sleeve 15 and reservoir will be lowered and raised while the lamp is indexed to a position therebelow. It may be here observed that cylindrical reservoir 14 is made to be removable from the bearing sleeve 15 for cleaning or other purposes and for that reason is shown with a downwardly directed peripheral shoulder 20 near the top end thereof of which seats on the upper end of the sleeve 15. Contiguous to the lower end of the sleeve, the cylindrical reservoir 14 has an external peripheral groove 21 which receives a resilient split ring 22 which also protrudes therefrom to underlie the lower end of the said sleeve 15 in engagement therewith. The reservoir is therefore held in the sleeve and consequently will reciprocate therewith in use.

The bottom end of the reservoir 14 (Figs. 2 and 3) has a large threaded hole 23 therethrough which receives a threaded neck 24 of a nozzle casing 25 coaxial to the reservoir and depending therebelow. Below the neck 24 said casing widens to provide a shoulder 26 facing upwardly toward the bottom of the reservoir. A gasket 27 between said shoulder and reservoir prevents leakage of flux 28 or other contents of the reservoir.

Longitudinally slidable within the nozzle casing 25 (Figs. 1-3 and 6) is a coaxial tubular nozzle 29. The lower end of this nozzle receives a dauber 30 therein which also protrudes for part of its length below the lower end of the nozzle. Said dauber is of suitable soft absorbent or spongy material, such as felt, sponge rubber and the like of a character which will absorb and retain flux fed thereto from above and surrender a given quantity thereof at its lower end when pressed against a surface. Above the dauber, the passageway 31 in the nozzle 29 is somewhat smaller in diameter so the dauber cannot be pushed inward beyond its intended position.

The lower end portion of the interior of the nozzle casing 25 and exterior of the nozzle 29 have a sliding fit, and thereabove the nozzle casing has an enlarged bore 32 which accommodates a peripheral rib 33 on the exterior of the nozzle. A compression spring 34 is located in said enlarged bore 32 above said rib and bears upon said rib to hold the nozzle normally in its downward position with the rib also acting as a stop by engagement with the bottom of the enlarged bore. Further upward of the nozzle casing the interior bore is again increased in diameter and provides an interiorly threaded hollow 35 extending upwardly to open at the upper end of neck 24. A bushing 36 of greater outside diameter than said enlarged bore 32 is located in said hollow 35 and seats against the bottom thereof. It may be noted in this connection that aforementioned compression spring 34 bears at its upper end against the under face of said bushing 36. Said bushing has a sliding fit at its interior with the exterior cylindrical surface of nozzle 29 and may furthermore be provided with an interposed ring seal 37 around the nozzle and an exterior ring seal 38 around the bushing 36 and in the nozzle casing 25.

Screwed into the threaded hollow 35 (Figs. 2 and 3) at the upper end of nozzle casing 25 is a nipple 39 which seats at its lower end against said bushing 36 for holding the bushing in fixed position, and which projects at its upper end into the bottom of the reservoir 14 in spaced relation away from the side wall thereof. Said nipple is hollow and cylindrical and coaxial to the reservoir and to the nozzle. A plurality of lateral orifices 40 are provided through the sides of said nipple 39 for admitting fluid, such as the flux 28, from the reservoir to the interior

of the nipple. A foraminous cylinder or strainer 41 of fine mesh girdles said nipple and overlies said orifices 40. The mesh of the strainer 41 is appropriate to admit normal passage of the fluid, but small enough to offer impedance to rapid flow from sudden pressure. A cap 42 has screw thread engagement with the upper end of nipple 39 to seal the nipple thereat, said cap also functioning to hold the strainer 41 from displacement from the nipple.

Within the nipple 39 there is provided a valve housing 43 (Figs. 2, 3 and 5) which is tubular and threaded onto the upper end of nozzle 29, said housing having an internal downwardly facing valve seat 44 adjacent to its upper end. A valve head 45 is located within said housing adjacent to and adapted to close against said valve seat in normal position under influence of a compression spring 46. Said spring is within said housing 43 and rests at its lower end against the upper end of nozzle 29 and presses at its upper end against the under face of the valve head. A valve stem 47 integral with said valve head projects upwardly through the valve seat and terminates in proximity to the under side of the cap 42 which closes the upper end of nipple 39. The relationship is such that spring 46 holds the valve head 45 normally closed against the valve seat, but when the nozzle 29 is pushed upward the said stem 47 engages said cap 42 and keeps the valve head 45 from continuing upward movement so that further upward movement of the nozzle opens the valve to passage of fluid 28 to the interior of the valve housing 25 and nozzle 29.

In view of the construction described, upward movement of the nozzle 29 functions as a plunger and decreases the volume capacity available within the subdivision of the reservoir 14 comprised within the nipple 39, and consequently obtains a differential of increased pressure therein from the normal pressure exerted by the head of fluid 28 in the reservoir, due in part to the impedance to escape of fluid back to the reservoir through the strainers 41. A spurt of fluid is therefore injected through the valve into the valve housing 43 and nozzle 29 each time the nozzle is forced upward and the valve opening is made to pass, each time, just the requisite amount to satisfy the need of the dauber 30 for a single application of flux. The fluid in the valve housing 43 and nozzle 29 is not under pressure so that its gravity flow to the dauber 30 does not cause the dauber to drip or to apply an excess of flux to the surface being treated. The mass of fluid within the nipple 39 is small enough and adequately confined to not be adversely influenced by momentum or creation of waves to interfere in the least with repetitiously constant amount of fluid passing to the nozzle 29. Furthermore, since it is primarily the plunger action of the nozzle 29 and valve housing 43 which causes injection of the dosage of flux past the valve seat 44, variation in the head of fluid in the reservoir makes no material change in the quantity injected each time the valve operates. Since the reservoir moves up and down and contains a considerable volume of fluid, a cover 48 is preferably provided to not only keep the fluid from becoming contaminated, but also to keep it from splashing out of the reservoir.

Finally, it is to be observed that the lamp 12 (Figs. 1-3) has a center terminal comprising a disc or other circular metallic end member 49 through which a lead-in wire 50 projects, and that it is the purpose of the device of this invention to apply flux to said member and wire so that, at a subsequent station as the machine indexes, said member 49 and wire 50 may be soldered. The dauber is of a diameter less than that of the disc 49 and is squeezed down onto the disc only enough to extrude a limited required amount of the flux 28 from the dauber. The resiliency of the dauber not only permits the squeezing action but also accommodates the projecting end of the lead-in wire. The limited area of contact of the dauber 30 and the limited feed of flux 28 thereto confines the

flux within the area of the disc 49 and promotes proper soldering likewise within the confines of the disc area.

We claim:

1. A device for fluxing an article comprising a reservoir for fluid flux, a nozzle projecting from said reservoir, valve means on said nozzle for admitting a predetermined amount of fluid flux to said nozzle from said reservoir, means between said reservoir and said valve means for impeding the rapid flow of fluid flux from said reservoir to said valve means due to sudden pressure and a dauber in the outer end of the nozzle adapted to absorb said predetermined amount of fluid flux as fed to the nozzle through said valve means from the reservoir, means for reciprocating said reservoir toward said article to cause said dauber to engage and be compressed against said article to flux said article and to cause said nozzle to move with respect to said reservoir to open said valve means and permit the passage of said predetermined amount of fluid flux to said nozzle from said reservoir.
2. A device for fluxing an article comprising a reservoir for fluid flux having an internal nipple therein constituting a subdivision of the interior of said reservoir, a nozzle reciprocable in said reservoir and having means to normally project the nozzle outwardly of said reservoir, valve means on said nozzle within said subdivision for admitting a predetermined amount of fluid flux to said nozzle from said reservoir, said valve means comprising a valve housing provided with a valve seat, a valve head engageable with said seat and protruding from said housing and means to normally project the valve head inwardly of the reservoir to seat said valve head on said valve seat, stop means on said nipple engageable with said valve head to unseat the valve head and admit said predetermined amount of fluid flux to said nozzle, and means for reciprocating said reservoir toward said article to cause said dauber to engage and be compressed against said article to flux said article and to cause said nozzle and said valve housing to move with respect to said reservoir and said valve head to engage said stop means thereby opening said valve means and permitting the passage of said predetermined amount of fluid flux to said nozzle from said reservoir.
3. A device for fluxing an article comprising a reservoir for fluid flux having an internal nipple therein constituting a subdivision of the interior of said reservoir, a nozzle reciprocable in said reservoir and having means to normally project the nozzle outwardly of said reservoir, valve means on said nozzle within said subdivision for admitting a predetermined amount of fluid flux to said nozzle from said reservoir, said valve means comprising a valve housing provided with a valve seat, a valve head engageable with said seat and protruding from said housing and means to normally project the valve head inwardly of the reservoir to seat said valve head on said valve seat, stop means on said nipple engageable with said valve head to unseat the valve head and admit said predetermined amount of fluid flux to said nozzle, a dauber in the outer end of the nozzle adapted to absorb said predetermined amount of fluid flux as fed to the nozzle through said valve means from the reservoir, and means for reciprocating said reservoir toward said article to cause said dauber to engage and be compressed against said article to flux said article and to cause said nozzle and said valve housing to move with respect to said reservoir and said valve head to engage said stop means thereby opening said valve means and permitting the passage of said predetermined amount of fluid flux to said nozzle from said reservoir.
4. A device for fluxing an article comprising a reservoir for fluid flux having an internal nipple therein constituting a subdivision of the interior of said reservoir, a nozzle reciprocable in said reservoir and having means to normally project the nozzle outwardly of said reservoir, valve means on said nozzle within said subdivision for admitting a predetermined amount of fluid flux to

said nozzle from said reservoir, said valve means comprising a valve housing provided with a valve seat, a valve head engageable with said seat and protruding from said housing and means to normally project the valve head inwardly of the reservoir to seat said valve head on said valve seat, stop means on said nipple engageable with said valve head to unseat the valve head and admit said predetermined amount of fluid flux to said nozzle, means between said reservoir and said valve means for impeding the rapid flow of fluid flux from said reservoir to said valve means due to sudden pressure, and a dauber in the outer end of the nozzle adapted to absorb said predetermined amount of fluid flux as fed to the nozzle through said valve means from the reservoir, means for reciprocating said reservoir toward said article to cause said dauber to engage and be compressed against said article to flux said article and to cause said nozzle and said valve housing to move with respect to said reservoir and said valve head to engage said stop

means thereby opening said valve means and permitting the passage of said predetermined amount of fluid flux to said nozzle from said reservoir.
